VALVE AND HEAT EXCHANGER UNIT

Frank E. Carroll, Jr., Harry T. Booth, and Kenneth O. Parker, Dayton, Ohio, assignors to United Aircraft Products, Inc., Dayton, Ohio, a corporation of Ohio

Application October 24, 1955, Serial No. 38,531

Term of patent 14 years

(Cl. D77—1)

Fig. 1 is a perspective view of a valve and heat exchanger unit embodying our new design;
 Fig. 2 is a top plan view thereof;
 Fig. 3 is a view in side elevation thereof;
 Fig. 4 is a view in elevation of one end thereof; and
 Fig. 5 is a view in elevation of the other end thereof.
 We claim:

The ornamental design for a valve and heat exchanger unit, as shown.
